INFANT'S DIAPER SUBSTITUTE

Lee Cohn, San Francisco, Calif., assignor of forty-nine per cent to L. J. Miller, San Francisco, Calif.

Application July 20, 1940, Serial No. 346,580

12 Claims. (Cl. 128—284)

The present invention relates to sanitary devices, and particularly to a substitute for diapers for babies.

Babies and small infants who have not yet learned to control the passage of urine and movement of the bowels require some convenient sort of device to protect the bed linen and clothing. The conventional answer to the problem is the diaper, a cloth folded to fit the child comfortably, and of a semiabsorbent nature, so that it will hold the secretions until such time as it can be replaced by a fresh one.

Such diapers require frequent changing and very careful washing and sterilizing before being used again. The labor involved in caring for them is a heavy burden on those charged with the care of the child.

In hospitals or other establishments where large numbers of babies are cared for together, the diapers require exceptionally thorough treatment to prevent the spread of various types of disease from one baby to another and from the outside. The problems of the household are multiplied when infants are cared for in institutions.

The labor and inconvenience in the handling of diapers has lead to numerous attempts to devise a satisfactory substitute. Some recent efforts have been aimed at the employment of treated cellulose sheets which would be used but once and then thrown away. These have not been widely accepted, since the results obtained in proportion to the increased cost have not been entirely satisfactory. Even the use of such materials as liners for the ordinary diaper have not become popular or widely used.

Certain devices have been made to hold the urine and the stool in separate compartments of rubber or similar material, but they have not been able to overcome the difficulty of maintaining the proper alignment of the receptacle portions with the secreting organs without uncomfortably constraining the baby. Further, the structures have been such that the cleansing of them has been provocative of more trouble than the conventional diapers. Again the harness or supporting strap system of such devices has been complicated, objectionable and unduly restrictive.

Various other substitutes have been devised which are known to those familiar with the art, but all of them have been open to objections so serious as to prevent their wide-spread adoption.

The present invention comprises a yielding

5 container made to receive the urine and fecal discharges and to hold them away from contact with the skin, particularly with reference to urine. The arrangement does not require, however, any elaborate precautions to align the receiving portions with the respective discharge organs of the baby, nor can they be easily twisted or pulled into such position that the container will have its function impaired. It is preferable to make the device of a soft, impervious material such as rubber, reinforced at necessary or convenient places to maintain the desired shape, and arranged to retain the discharged material without restricting the baby.

10 The details of the invention may be understood more fully by reference to the drawings wherein

Fig. 1 is a posterior view of a preferred embodiment of my invention in position on a baby;

20 Fig. 2 is an anterior view of a modified form of my invention in position on a baby;

Fig. 3 is a longitudinal sectional view of the embodiment shown in Fig. 1;

25 Fig. 4 is a top view of the device shown in Fig. 3, with portions cut away;

Fig. 5 is a fragmentary sectional view of the structure taken as indicated by line 5—5 in Fig. 3;

30 Fig. 6 is a side view, partially in section, of the embodiment of Fig. 2;

Fig. 7 is a top view of the device shown in Fig. 6;

35 Fig. 8 is a fragmentary sectional view illustrating a preferred shape of rim, taken as indicated by arrows 8—8 in Fig. 6;

Fig. 9 is a fragmentary sectional view of a modified shape of rim;

Fig. 10 is a fragmentary sectional view of another rim structure.

40 From inspection of the drawings and from the description which follows, it will be seen that the primary object of the invention is to provide a satisfactory substitute for a baby's diaper.

Some of the other objects are: to provide a 45 receptacle for holding temporarily the urine and stool discharged by a baby; to provide a substitute for diapers which can be readily cleansed and disinfected; to reduce possibility of spreading infectious diseases through diaper contact;

50 to prevent soiling of clothes and bed linen by involuntary discharges of urine and fecal matter; to provide a sanitary device which may be used by persons of any age who are afflicted with incontinence or lack of control of the bladder and bowels; to provide a sanitary substitute for

a bed pan for those persons who are unable to make use of the conventional types; to provide an easily portable container for stools and urine which may be attached without discomfort to the user; to provide a diaper substitute which requires no elaborate harnesses for its support; to provide a diaper substitute which may be readily manufactured of easily procurable materials having great resistance to corrosive secretions; to provide a diaper substitute which retains discharged matter out of contact with the skin of the user; to provide a diaper substitute preventing leakage regardless of moderate displacement from its optimum position; and to provide for the effective drainage of secretions into the proper repository in various positions of the wearer.

Additional objects will be apparent to those skilled in the art, and such changes of form, proportion, and structures as are necessary to adapt my device to such objects are deemed to form a part of the present invention.

Referring now to the drawings for a detailed description of the invention, there is shown from the rear a preferred form of a device in position in Fig. 1, comprising a unitary rubber container 1 shaped to fit around the external urinary and fecal organs of the baby or other user, and to be held in position by means such as a resilient belt 2 fastened around the waist of the wearer 4 and attached to the container 1 by suitable clasps 5 at front and rear. The embodiment shown anteriorly in Fig. 2 will be explained later in connection with Figs. 6 and 7.

Container 1 depends from a rim 6, molded of relatively heavy rubber or similar material shaped to fit snugly over the lower portion of the user's abdomen in front, as shown in Fig. 2, around the crotch, and over a substantial portion of the buttocks, as shown in Fig. 1. A groove 7 may be molded into rim 6, facing inwardly throughout to provide a firm but yielding contact with the body of the user. When the rim 6 is pressed against the skin, groove 7 becomes a low pressure vacuum cup, tending to hold the rim more tightly to the body. Two shoulders 8 lying on each side of the groove 7 are thus in position to act as sealing members.

From the rim 6 hangs an inner trough 9 of firm rubber or similar material having a large number of small perforations 10. These perforations may be distributed over the entire area. A diaphragm 11 may be set across the trough or pouch 9 somewhat forward of its median portion, dividing the pouch into a front or urine-receiving portion 12 and a rear faeces cradle portion 14. It is not essential that the device be used in such position that all the urine is deflected away from immediate contact with the faeces by the diaphragm 11. Hence the diaphragm 11 may be eliminated if desired. The numerous perforations 10 allow all of the liquid discharge to drain out of the trough 9 into urinary compartment A and thence into compartment B, while retaining the faeces in cradle 14.

The trough or pouch 9 may be formed integrally with the rim 6, or may be joined thereto by any method which will produce a liquid-tight connection. Adjacent the line of attachment between trough or pouch 9 and rim 6, the latter is joined by similar means to an inner pouch 15, which completely surrounds the trough or pouch 9, and receives the liquid seepage therefrom. Thus urinary compartment A is formed.

Inner pouch 15 is pierced by a comparatively small number of relatively large perforations 16. Through them the liquid entering the inner pouch 15 is rapidly passed on to outer pouch 17, which is urinary compartment B. The outer pouch is also secured to, or formed integrally with, the rim 6, and is elongated both front and rear therebeyond. The purpose of such elongation is to make sure that, regardless of the position in which the baby is lying, a part of pouch 17 will lie below the trough 9 and pouch 15, thus ensuring a gravity drainage into the storage, or outer, pouch 17. It will be seen that elongating the pouch 17 beyond a vertical line through the uppermost portions of rim 6 accomplishes this result. If the child is lying prone, the forward portion 19 of the pouch 17 will be lower than trough 9; if supine, the rear portion 20 of the pouch 17 will lie beneath the trough; while if upright, the entire pouch is in receptive position.

The provision of fewer apertures 16 between receptacles 15 and 17, and wider spacing than in the case of the trough and feces cradle, acts to confine the liquid matter to the outer compartment 17. If compartment 17 becomes overly full, there could occur a reverse flow in some positions, but sufficient capacity is provided so that under normal conditions there will be no return passage.

Likewise, it is contemplated that the device may be provided with small check valves placed in the perforations 16 which prevent return flow under any circumstance.

A portion of pouch 17 is reinforced and threaded to form a drain 21 for the removal of the liquid wastes and to permit ready cleansing. In use, drain 21 may be closed by a screw plug 22.

Additional reinforcements may be provided to maintain the proper shape of the container, such as a rib 24 molded around the median line of pouch 17. The feces cradle 9 may also be reinforced at the rear by ribs, not shown, or by using a slightly stiffer material section to prevent the material from clinging too closely to the buttock area.

A simpler and less expensive form of the present device would eliminate the urine compartment A. Such adjustments as would be required to adapt the broad concept of the present invention to such form are contemplated herein.

A number of very fine ventilating apertures 25 may be formed through or below the rim 6 to provide ventilation, but should not be large enough to permit passage of liquids.

The rim 6 is extended medially to form a front tab 26 and a rear tab 27 having perforations 28 for easy and ready attachment by clasps 5 to the supporting belt 2. Any suitable means of attachment may be provided.

From the description above it will be seen that a wide latitude is possible in the positioning of the device, since even if it is not in its normal location, the rim and the laterally enlarged front and rear portions will be in sealing position and capable of receiving all discharges from the infant without danger of spillage.

It will be observed that the device, by changing its dimensions, is equally suited to use by adults who require sanitary protection.

Referring now to the embodiment of Figs. 2, 6 and 7, there is illustrated an embodiment which permits a smaller device to be used in cases where it is possible to support a holding container by attaching it to a leg, for example, or

where portability is not desired and any kind of holding or disposal facility is available.

In this embodiment, a similar structure is used for the frame 6 and the pouch 9. Inner pouch 36 is made somewhat larger than in the previous embodiment and it may be desirable to form a larger number of drainage apertures 31 therethrough. These drainage apertures 31 may likewise be provided with small check valves to prevent possibility of return flow. Outer conduit 32 is formed along the median line of pouch 30, and provides no storage space, but merely acts as a collecting conduit, leading the accumulated liquid wastes into front and rear discharge conduits 34 and 35 respectively. The conduits 34 and 35, which may be conventional rubber tubing, may be joined at will with a common conduit 36, in turn leading to a rubber bag 37 or other discharge container. If desirable, the bag 37 may be attached to the leg of the individual by straps 38 and a check valve 39 is provided to prevent the bag from being emptied back into the tube 36, while permitting gases to escape from the bag. Such valves are known to the art, and a detailed description will not be given, since it forms no part of the instant invention. Obviously, a single conduit from the outer pouch 32 might be used, but I prefer to have both front and rear outlets to insure rapid drainage in either the prone, supine or erect positions.

In some devices it may be advantageous to use a sponge-rubber construction for the rim 6, but any suitable material may be used. The shape of the rim may be varied also. Fig. 9 shows a rim having a single rounded rib 40 instead of the grooved type shown in Fig. 8. I have also found a wedge-shaped or triangularly beaded rim 41, as shown in Fig. 10, to be satisfactory. Particularly in those cases where a softer material is used for the rim, a core 42 of wire or other material may be molded in to hold the desired contour of the rim and shape it to the body of the user.

The upper compartment or trough 9 may be provided with a highly absorbent material such as cellulose for containing the greater mass of urine and fecal discharges. The form is preferably a disposable pad shaped to fit the entire compartment or if the diagram 11 is employed then the disposable pads would be shaped to fit the individual compartments. The urine containers such as A and B would provide capacity for the extra urine not capable of being absorbed by the pad.

The pads of absorbent material may be treated with an antiseptic or deodorant, such as boric acid (powder), and can be manufactured for economical use. With the use of such pads, some convenience may be added for employment of the device in certain instances.

From the above description, it will be seen that I have invented a diaper substitute which can be readily cleansed and used, and which requires a minimum of harnesses to support it. Obviously, the device shown may be attached to any type of baby garment or other supporting means available, but the belt shown is a simple and convenient form of support.

The device can be manufactured easily of material which will resist the corrosive and deteriorating effects of bodily secretions, and which can be easily cleaned and disinfected. It aids the health and comfort of the baby by removing the liquid secretions from contact with the skin,

and thus prevents one of the causes of chafing and irritation.

It is useful not only for babies, but also for those older children or adults who are unable to exercise control over their eliminative functions or who are confined to bed and find it difficult to use the ordinary sanitary devices.

The use of my device relieves the mother or attendant from the labor and inconvenience of handling and laundering diapers, and removes a source of infection by the ease with which cleansing and disinfecting are accomplished, and further brings out a tremendous economy in the handling of such body discharges.

15 It is neither reasonable to demand that an inventor know all of the art at the present time upon which he may have supposedly selected the words of this disclosure nor possible for any human to anticipate what direction the future development of the art may take, which may make the language used inapt. Therefore, the disclosure of this invention should not be construed as limited by the words used and, further, the substance should not be confined to the precise forms in the drawings illustrating this invention. It is contemplated that changes of form may be made, with variations and departures from the illustrated forms, without departing from the scope of this invention. Such variations and departures include those made possible by discovery of improved materials and better uses and forms of present materials, as well as practices and results which may be possible in actual commercial fabrication and handling.

35 I claim:

1. A diaper substitute, comprising discharge-receiving means arranged to enclose the urinary and fecal organs, means for maintaining and discharge-receiving means in sealing relation about said organs, drainage means formed through said receiving means, an inner enclosure surrounding said receiving means, substantially unidirectional drainage means associated with said inner enclosure, an outer enclosure surrounding said inner enclosure, an outlet formed in said outer enclosure, and means for closing said outlet.

2. A diaper substitute, comprising discharge-receiving means arranged sealingly to enclose the urinary and fecal organs, means permitting drainage of liquids from said discharge-receiving means, means for effecting a primary separation of urine and feces in said discharge-receiving means, an enclosure surrounding said discharge-receiving means, spaced drainage apertures formed through said enclosure, an outer enclosure surrounding said enclosure, a drainage port formed in said outer enclosure, and means for closing said port while said diaper substitute is in use.

3. A diaper substitute, comprising a perforated trough shaped to enclose the urinary and fecal organs, a diaphragm extending laterally across said trough, a plurality of drainage apertures distributed throughout said trough, an inner enclosure surrounding said trough, drainage apertures distributed in said enclosure, an outer enclosure surrounding said inner enclosure, a drainage port formed in said outer enclosure, and means for closing said port while said diaper substitute is in service.

4. A diaper substitute, comprising a discharge-receiving trough shaped to enclose the urinary and fecal organs of a human being, a diaphragm extending transversely across said trough, a rim

arranged to fit sealingly against a user formed peripherally about said trough, a plurality of ventilating apertures formed through said rim, and a plurality of drainage apertures formed throughout said trough, an inner enclosure formed integrally with said rim and surrounding said trough, spaced drainage apertures in said inner enclosure, an outer enclosure formed integrally with said rim and surrounding said inner enclosure, a drainage port formed in said outer enclosure, and means for plugging said port.

5. A diaper substitute, comprising a trough, a rim arranged to fit snugly against the skin around the urinary and fecal organs, a diaphragm extending transversely of said trough between said organs, ventilating means formed in said rim, and a plurality of drainage apertures formed in said trough, an inner enclosure formed integrally with said rim and surrounding said trough, spaced drainage apertures through said inner enclosure, an outer enclosure surrounding said inner enclosure and formed integrally with said rim, a drain formed in said outer enclosure, means for closing said drain, and means associated with said rim for supporting said diaper substitute.

6. A diaper substitute, comprising a trough, a rim arranged to fit snugly against the skin around the urinary and fecal organs, and laterally over the lower abdomen and over a portion of the buttocks of the wearer, ventilating means formed in said rim, and a plurality of spaced drainage apertures formed in said trough, an inner enclosure formed integrally with said rim and surrounding said trough, spaced drainage apertures through said inner enclosure, an outer enclosure surrounding said inner enclosure and formed integrally with said rim, a drain formed in said outer enclosure, means for closing said drain, and means associated with said rim for supporting said diaper substitute.

7. A diaper substitute, comprising a trough, a rim arranged to fit tightly against the skin around the urinary and fecal organs, and over the lower abdomen and a portion of the buttocks of the wearer, a diaphragm extending transversely of said trough between said organs, ventilating means formed in said rim, and a plurality of spaced drainage apertures formed in said trough, an inner enclosure formed integrally with said rim and surrounding said trough, spaced drainage apertures through said inner enclosure, an outer enclosure surrounding said inner enclosure and formed integrally with said rim, and extending substantially forward and backward of the uppermost front portion and the uppermost rear portion, respectively, of said rim, a drain formed in said outer enclosure, means for closing said drain, and means associated with said rim for supporting said diaper substitute.

8. A diaper substitute, comprising a trough, a rim arranged to fit snugly against the skin around the urinary and fecal organs, and over the lower abdomen and a portion of the buttocks of the wearer, ventilating means formed in said rim, and a plurality of spaced drainage apertures formed in said trough, an inner enclosure formed integrally with said rim and surrounding said trough, spaced drainage apertures through said

inner enclosure, an outer enclosure surrounding said inner enclosure and formed integrally with said rim, and extending substantially forward and backward of the uppermost front portion and the uppermost rear portion, respectively, of said rim, means for maintaining said outer enclosure in fully extended position, a drain formed in said outer enclosure, means for closing said drain, and means associated with said rim for supporting said diaper substitute.

9. A diaper substitute, comprising discharge-receiving means arranged to enclose the urinary and fecal organs, means for maintaining said discharge-receiving means in sealing relation about said organs, drainage means formed through said receiving means, an inner enclosure surrounding said receiving means, substantially undirectional drainage means associated with said inner enclosure, an outer enclosure surrounding said inner enclosure, a front drainage aperture and a rear drainage aperture formed in said outer closure, drainage conduits leading from said front and rear drainage apertures, and storage means associated with said drainage conduits.

10. A diaper substitute, comprising drainage-receiving means arranged sealingly to enclose the urinary and fecal organs, means permitting drainage of liquids from said discharge-receiving means, means for effecting a primary separation of urine and feces in said discharge-receiving means; an enclosure surrounding said discharge-receiving means, a few widely spaced drainage apertures formed through said enclosure; an outer enclosure surrounding said enclosure, a front and a rear drainage aperture formed in said outer enclosure, conduits extending from said front and rear drainage apertures, and temporary storage means connected to said conduits.

11. A diaper substitute, comprising a perforated trough to enclose the urinary and fecal organs, a plurality of drainage apertures distributed throughout said trough; an inner enclosure surrounding said trough, a plurality of drainage apertures distributed in said enclosure, an outer collecting enclosure communicating with said inner enclosure by means of said drainage apertures, front and rear drainage tubes leading from said outer collecting enclosure, and storage means connected to said tubes.

12. A diaper substitute, comprising a discharge-receiving trough to enclose the urinary and fecal organs of a human being, a diaphragm extending transversely across said trough, a rim arranged to fit sealingly against a user formed peripherally about said trough, a plurality of ventilating apertures formed near said rim, and a plurality of spaced drainage apertures formed throughout said trough, an inner enclosure formed integrally with said rim and surrounding said trough, a plurality of spaced drainage apertures formed in said inner enclosure, an outer collecting enclosure communicating with said inner enclosure by means of said drainage apertures, drainage conduits associated with said outer collecting enclosure forwardly and rearwardly thereof, and storage means associated with said drainage conduits.

LEE COHN.
